Primary Examiner — Mary Ann Calabrese*Assistant Examiner* — Natalya M Rapundalo(74) Attorney, Agent, or Firm — Bochner IP, PLLC;
Andrew D. Bochner(57) CLAIM

The ornamental design for a water pot, as shown and described.

DESCRIPTION

FIG. 1 is a front perspective view of a water pot showing our new design;

FIG. 2 is a top plan view thereof; and,

FIG. 3 is a top, right, perspective view thereof.

The broken lines in the drawings illustrate portions of the water pot and form no part of the claimed design.

1 Claim, 3 Drawing Sheets
